UNITED STATES PATENT OFFICE.

JAMES ARMSTRONG, OF TOLEDO, OHIO.

IMPROVEMENT IN MECHANICAL MOVEMENTS.

Specification forming part of Letters Patent No. 142,365, dated September 2, 1873; application filed August 21, 1873.

To all whom it may concern:

Be it known that I, JAMES ARMSTRONG, of Toledo, in the county of Lucas and State of Ohio, have invented certain new and useful Improvements in Mechanical Movements, of which the following is a specification:

My invention relates to a mechanical movement for gaining motion for driving machinery without the usual loss of leverage.

The improvements claimed will be herein-after specified.

In the accompanying drawings, Figure 1 is a side elevation of my improved machine; Fig. 2, a similar view from the opposite side. Fig. 3 is a plan view, Fig. 4 an elevation, and Fig. 5 a top view, of details of the machine; and Fig. 6, a vertical section through the main shaft on the line $x x$ of Fig. 1.

A spur-pinion, A, driven in any suitable manner, is mounted on a shaft, a, supported securely in uprights of a strong frame, B. This pinion drives a corresponding pinion, C, mounted on a sleeve, c, secured in proper position by a set-screw upon a pipe-box, D, fitted upon a stationary central shaft, E, which is securely mounted in the frame B. By means of the sliding sleeve and set-screw the pinion C can readily be removed. Upon the pipe-box D are fixed two pulleys, F F', so as to turn with the pinion C upon the stationary shaft E. Adjoining the pulley F' is a stationary pinion, G, firmly fixed upon the central shaft. A transmitting-wheel, H, is mounted loosely upon the central shaft E close to the fixed pinion G. This wheel is provided with an internally-gearred flange, g, its teeth corresponding with those of pinion G. A frame, I, is mounted loosely on the central shaft. This frame preferably embraces or incloses the pulley F' and pinion G, and carries a pinion, J, in this instance corresponding in size with the fast pinion G. This pinion J meshes with the pinion G and with the wheel H. A pulley, J', is fast on the same shaft j with the pinion J. A bracket, K, secured to the frame I carries a pulley, k.

It will be seen that as the pinion A revolves motion is communicated to the pinion C and to the pulleys F F'. A belt, f, passing from the pulley F' to the pulley J' and around the pulley k, communicates motion to the pinion

J, which is thus revolved twice on its axis for every revolution around the central shaft. As the pulleys F, F', and J', the power from the first of which is communicated through the second to the third, are all of the same size, there is no loss of power, as it is communicated to the surface of each at an equal distance from its center.

In Figs. 2 and 3 I have shown a belt passing from the pulley N on the pipe-box to a loose pulley, O, corresponding with the pulley k, and another belt passing from this pulley to another pulley, P, corresponding with the pulley J', which is fast on the same shaft with the friction-pulley Q, corresponding with the pinion J. The two revolutions only of the pinion J on its own axis are caused by means of the bodily movement of the pinion and its frame around the central shaft, and by the fixed pinion G, with which it engages.

It is obvious that as the pinion J, in its revolution, describes a circle three times the diameter of the pulley F', it should revolve three times on its own axis for every revolution around the central shaft. The last revolution is transmitted to the wheel H. The wheel H, it will be seen, makes one revolution to every revolution and a half of the pinion C, which is, in this instance, one-third the size of the wheel H; or, in other words, the speed is doubled.

By the use of the pulley k the belt f is caused to draw in the direction of the revolution of the wheel H, thus causing the band to work to better advantage than it would in case this pulley was dispensed with.

Instead of the counter-balance L of the frame I, another pulley similar to J', and pinion such as J, may be substituted, and a pulley such as k employed, as shown in Fig. 4.

It is obvious that the pinions, pulleys, and internally-gearred wheel may be of different relative sizes than have been here shown.

The machine above described is complete, and all that it is now necessary to do is to carry a belt from the wheel H to the machinery to be driven, unless a still greater speed is desired, in which case the belt from the wheel H is carried to a pulley, M, on the shaft of a second machine operating on the same principle as the one just described, the gearing used in

this machine being frictional instead of toothed. I thus get double the speed from the transmitting-wheel of the second machine that is gained from the first, and four times as much as from the pinion C.

I claim—

1. The combination of the loose pulley turning on the fixed central shaft, the loose pulley-frame, also turning on said shaft, the connected pulley and pinion mounted in said frame and revolved by a belt from the pulley on the central shaft, the fast pinion and the loose transmitting-wheel, both mounted on said shaft, substantially as set forth.

2. The combination of the stationary pinion on the fixed central shaft, the loose transmitting-wheel on said shaft, and the pinion meshing with both the fixed pinion and transmit-

ting-wheel, and turning both on its own axis and around the central shaft, substantially as set forth.

3. The combination of the fixed central shaft, the connected pinion and pulleys turning thereon, the frame also turning on said shaft, the connected pulley and pinion turning in the frame, the pulley mounted in a bracket on the frame, and the belt, these parts being constructed and arranged to operate substantially as set forth.

In testimony whereof I have hereunto subscribed my name.

JAMES ARMSTRONG.
